DENTAL ENGINE ATTACHMENT.

J. E. MORGAN.
PATENTED APR. 4, 1906.

No. 786,662.

UNITED STATES PATENT OFFICE.

JOHN E. MORGAN, OF EMPORIA, KANSAS.

DENTAL-ENGINE ATTACHMENT.

SPECIFICATION forming part of Letters Patent No. 786,662, dated April 4, 1905.
Application filed August 12, 1904. Serial No. 220,537.

To all whom it may concern:

Be it known that I, JOHN E. MORGAN, a citizen of the United States, residing at Emporia, in the county of Lyon and State of Kansas, have invented a new and useful Improvement in Dental-Engine Attachments, of which the following is a specification.

My invention is in the nature of a dental-engine attachment designed to furnish a continuous blast of air to blow the chips from the cavity of a tooth as fast as they are drilled, thereby saving much time by rendering it unnecessary to stop the drill for this purpose and also reducing the pain of this operation by keeping the drill cool and avoiding the heat due to friction.

My invention consists in a simple and novel fan-blower so constructed as to be mounted on the upper portion of the ordinary dental engine and be operated by the same belt which operates the drill and provided with a blast-tube leading to a nozzle mounted on the handpiece in such proximity to its drill as to properly direct the blast into the cavity of the tooth.

Figure 1 is a perspective view of a dental engine equipped with my attachment. Fig. 2 is an enlarged perspective view, partly broken away, showing the manner of mounting my attachment on the dental engine and operating it thereby; and Fig. 3 is a detail of the handpiece and blast-nozzle.

In the drawings, Fig. 1, A represents the treadle; B, the grooved fly-wheel; C, the upright standard; D, the horizontal shaft at the top thereof; E, the flexible power-shaft, and F the handpiece of the ordinary dental engine. In this engine a cord belt *b* extends from the grooved fly-wheel to a small pulley *d*, which is connected to shaft D and imparts axial rotation to the flexible shaft E and to the drill or other tool within the handpiece.

The upper end of the standard C is formed with a fork, (see Fig. 2,) between whose branches *a* is pivoted at *a'* the journal-frame D', which carries the end of the shaft D and its attached driving-pulley *d*. To the journal-frame D' is attached a downwardly-projecting and curved plate *a'*, having a circular slot *a''*

described about the pivotal center *a'*. Passing through this slot and through the neck of the fork *a* is a clamp-screw *a''*, by which the angular position of journal-frame D' and shaft D in relation to the standard C may be adjusted or regulated to suit the convenience of the dentist.

As so far described, the engine is of a well-known type. My attachment comprises a circular fan-case 1, which has formed on or attached to it an arm 4, projecting from the periphery of the fan-case at right angles to the case or parallel to the axis of the fan. This arm is slotted or forked at its outer end, and this slot receives the inner edge of the curved plate *a'*, and a screw 5 securely clamps arm 4 and the supported fan-case to the plate of the journal-frame D' of the engine. The fan-case arm 4 projects through or between the two branches *a a* of the fork, so that the fan-case is on the opposite side of the standard C from the plate *a'*. The fan-case 1 is provided with a central inlet-opening 8 on the outer side of the fan-case and has a tangentially-arranged discharge-spout 3 at the top, which spout connects with a flexible rubber hose 6. This rubber hose is connected at intervals along the flexible shaft E and at the end communicates with a detachable nozzle 7, (see Fig. 3,) detachably connected to the handpiece by a sleeve 10 and so positioned as to direct the blast of air to the point of the drill. Within the fan-case is a rotary fan 9, whose shaft extends through the inner side of the case and is provided with a small pulley 2, which bears against the cord belt *b* of the engine and derives therefrom a rapid rotation to cause the fan to send a strong blast of air through the hose-pipe 6 to the nozzle at the handpiece.

It will be seen that the special construction and arrangement of the fan-case and supporting-arm brings the fan in proper relation to be not only driven by the same belt which runs the drill, but also allows the fan attachment to follow the adjustments of the journal-frame D' and shaft D and forms a simple, compact, and practical device for the purpose intended.

22
 I am aware that air-blast devices have been heretofore used in connection with a dental engine, and I do not claim this idea broadly.

Having thus described my invention, what I claim as new, and desire to secure by Letters Patent, is—

1. A blowing attachment for a dental engine, comprising a rotary fan having a central intake-opening and a tangential spout, a pulley arranged on the fan-shaft, means for supporting the attachment on the dental engine and operating it from the dental-engine belt and a hose and nozzle for carrying the air-blast substantially as described.
- 15 2. A dental engine comprising in its construction an upright standard, a shaft-support secured to its upper end, a rigid shaft journaled in said support, a pulley fast on one end of the shaft, a flexible shaft operatively connected to the opposite end and a driving-belt passing around said pulley; in combination with a rotary fan arranged in a plane parallel to that of the shaft-pulley and on the opposite side of said pulley from the flexible shaft, and a driving-pulley arranged on the fan-shaft to bear against the dental-engine belt substantially as shown and described.
- 25 3. A dental engine comprising an upright standard, a forked support mounted on the

upper end of the same, a tilting frame arranged in said fork and bearing a shaft and its pulley, and a belt driving said pulley; in combination with a rotary fan having a supporting-arm extended between the forks of the dental engine and secured to the tilting frame, and a pulley for said fan operated by the dental-engine belt substantially as described.

4. A dental engine comprising an upright standard, a forked support mounted on the upper end of the same, a tilting frame pivoted in the forked support and having a curved, slotted, and downwardly-projecting plate with means for fixing its adjustment, a shaft with pulley mounted in the tilting frame, a belt for driving the pulley, a rotary fan having a central opening in its side and a tangential delivery-spout and an arm projecting at right angles to the fan and extended through the fork of the dental engine and secured to the curved and slotted plate and a pulley for the fan operated by the dental-engine belt substantially as shown and described.

JOHN E. MORGAN.
